UNITED STATES PATENT OFFICE

173,248

AIR CONDITIONER CABINET

Lawrence H. Wilson, Detroit, Mich., assignor to
Admiral Corporation, Chicago, Ill., a corpora-
tion of Delaware

Application January 25, 1954, Serial No. 28,648

Term of patent 14 years

(Cl. D62—4)

To all whom it may concern:

Be it known that I, Lawrence H. Wilson, a citizen of the United States, residing at Detroit, in the county of Wayne, State of Michigan, have invented a new, original, and ornamental Design for an Air Conditioner Cabinet, of which the following is a specification, reference being had to the accompanying drawings, forming a part hereof.

Fig. 1 is a perspective view taken from one side of an air-conditioner cabinet, showing my new design, the door being closed; and

Fig. 2 is also a perspective view thereof as viewed from the other side, the door being open.

The back of the cabinet is plain.

I claim:

The ornamental design for an air conditioner cabinet, as shown and described.
